CLAUS J. WERNER CLASEN, OF DAVENPORT, IOWA, ASSIGNOR TO THE BETTENDORF COMPANY, OF BETTENDORF, IOWA, A CORPORATION OF IOWA

STRUT PLATE

Application filed December 16, 1929. Serial No. 414,337.

This invention relates to railway car underframes and more particularly to the construction at the joint between the center sill and body bolster.

5 In the construction of car underframes, only a limited space for the underframe is available between the truck bolster and the car floor. The construction to which this invention relates provides a body bolster continuous in one piece from side to side of the car passing through a recess on the under side of the center sill with the bottom of the body bolster substantially flush with the bottom of the center sill and the center bearing projecting below the bottom of the sill.

On account of the recess in the under side of the sill to receive the body bolster, buffing forces or end shocks due to the operation of the cars are exerted on a line well below the neutral axis of that portion of the sill over the bolster recess and in many instances are on a line passing directly through this recess. These buffing forces set up bending stresses in the portion of the sill over the recess which after repeated buffing shocks will distort the sill due to the fact that foundry tolerances will not permit a tight fit of the body bolster in the recess.

30 The present invention has for its object to provide an elongated centrally widened strut plate which is rigidly connected to the under side of sill fore and aft of the recess and also to the under side of the body bolster, and is of sufficient strength to materially lower the neutral axis of the sill, of which it becomes a part, so that it will effectively resist the bending strains, and in addition, will assist the sill to carry the vertically applied loads imposed upon it by the freight contained in the body of the car.

40 A further object is to provide a strut plate which not only strengthens the recessed portion of the center sill but which also reinforces the draft extension of the center sill between the body bolster and draft gear pocket.

45 A further object is to provide a reinforcing strut plate which serves to strengthen the recessed portion of the sill and which also serves as a center plate providing an annular

bearing or seat between the truck bolster and the underframe of the car.

With the above and other objects in view, the invention may be said to comprise the structure as illustrated in the accompanying drawings hereinafter described and particularly set forth in the appended claims, together with such variations and modifications thereof as will be apparent to one skilled in the art to which the invention appertains.

55 Reference should be had to the accompanying drawings forming a part of this specification in which :

Fig. 1 is a fragmentary plan view showing a portion of the steel underframe of a railway car.

Fig. 2 is a section taken on the line indicated at 2-2 in Fig. 1.

Fig. 3 is a section taken on the line indicated at 3-3 in Fig. 1.

Fig. 4 is a section taken on the line indicated at 4-4 in Fig. 1.

Fig. 5 is a section taken on the line indicated at 5-5 in Fig. 3.

Fig. 6 is a plan view of the strut plate.

Fig. 7 is a sectional view showing a slightly modified construction.

Fig. 8 is a plan view of the strut plate shown in Fig. 7.

The car underframe comprises a center sill which may be of the single or double type being herein shown for purpose of illustration as an I-beam, and side sills 2 which are connected by body bolsters 3 and tie beams 4, Fig. 1 showing one end only of the underframe.

At each end, the center sill is provided with extensions 5 which may be formed separately from the body portion of the sill, in which case they are rigidly attached to the sill. The extensions 5 are spaced apart at their outer ends to provide spaced draft arms which accommodate a draft gear between them, the draft gear including the usual coupling member 7.

90 As herein shown, the extensions are formed separately from the body of the sill and are provided with channel shaped arms 8 at their inner ends which fit in the channels upon the opposite sides of the body portion of the cen- 95

ter sill, the flanges and webs of the channels being rigidly secured to the flanges and webs of the body portion of the sill. The extensions 5 when formed separately from the body of the sill are attached to the ends of the body portion of the sill immediately to the inner side of the body bolster and are provided with recesses 9 on the under sides thereof of a width and depth to receive the body bolsters 3 with the bottoms of the body bolsters substantially flush with the bottoms of the extensions 5.

The extensions 5 are preferably in the form of castings with integral webs 10 and 11 across the sides and tops of the bolster recesses for engagement with the sides and tops of the bolsters. A strut plate 12 is rigidly secured to the bottoms of the extensions 5 and to the body portion of the sill at each end thereof and these strut plates extend across the open lower end of the bolster recesses 9.

The strut plate may be formed to serve as a bearing member between the truck bolster and car underframe and when so formed, serves the purpose of the usual center plate as well as a sill reinforcing member. As shown in Figs. 1 to 6, each strut plate rests upon a truck bolster 13 and has a central annular depressed bearing portion 14 which rests in an annular bearing recess on the top face of the truck bolster formed by an outer annular rib 15 and an inner annular boss 16 concentric with the rib 15. The truck bolster is provided with a center pin aperture 17 within the annular boss 16 and the strut plate is provided with a central raised portion 18 forming a recess on the under side thereof to receive the boss 16 of the truck bolster, the raised portion 18 being provided with an aperture 20 which registers with the aperture 17 in the truck bolster. The annular depressed bearing portion 14 of the strut plate provides an annular channel in the top face of the plate and this channel is reinforced by ribs 22 and 23, the ribs 22 extending radially across the channel and the ribs 23 reinforcing the outer portion of the channel between the ribs 22.

The height of the reinforcing ribs 22 and 23 is less than the depth of the channel and the central raised portion 18 fits in a recess in the bottom of the body bolster, the body bolster and the sill extension above the body bolster being provided with center pin apertures 24 and 25 which are axially aligned with each other and with the apertures 17 and 20 of the truck bolster and strut plate.

The strut plate has an elongated raised portion 26 which extends a substantial distance along the underface of the body portion of the center sill and which is rigidly secured to the bottom thereof by riveting or other suitable means. To the outer side of the body bolster, the strut plate has an outwardly flaring raised portion 27 which is rigidly secured

to the underside of the extensions 5 and extends outwardly from the bolster recess to the draft gear pocket between the arms 6, the strut plate being provided with a central recess 28 at the end thereof to provide space to accommodate a draft yoke mounted between the arms 6. The strut plate also has laterally extending raised portions 29 extending from opposite sides of the central bearing portion which are rigidly secured to the bottom of the body bolster 3. The raised portions 26, 27 and 29 of the strut plate are connected by integral webs 30 and the side edges of the plate taper from the ends of the central lateral extensions 29 to the opposite ends of the plate, the side edges being preferably stiffened by short depending flanges 31.

The strut plate 12 is preferably a casting and by reason of its elongated longitudinal channels and short transverse channels connected by the side webs and flanges provides a very strong and rigid reinforcement for the recessed portion of the sill. The strut plate receives compression stresses due both to the superposed load on the extension of the sill and also due to the buffing forces exerted upon the ends of the sill. Since the strength of the strut plate is sufficient to compensate for the weakening of the sill by the transverse recess 9, the neutral axis of the sill will be materially lowered so that it extends through the bolster recess and buffing stresses will be exerted substantially along the neutral axis, so that, the portion of the sill immediately above the bolster recesses will be relieved of substantially all bending stresses and the sill extensions will not be distorted by buffing forces.

In Figs. 7 and 8 of the drawing, there is shown a modification of the invention in which a strut plate 34 of a slightly different construction is employed. In this instance, the strut plate is formed independently of the center plate and is provided with a central aperture 36 which is of a diameter sufficient to receive a center plate or other bearing member interposed between the truck and body bolsters.

The strut plate 34 is centrally widened to engage the body bolster on opposite sides of the sill and is provided at its inner end with an elongated raised portion 37 which extends along against the bottom of the body portion of the sill and is rigidly secured thereto by riveting or other suitable means.

The opposite end of the strut plate 34 is provided with a wider raised portion 38 which is rigidly secured to the bottom of the sill extensions and to the bottoms of the laterally spaced outer portions thereof, the latter end of the plate being provided with the central recess 39 to accommodate the draft yoke. In both modifications above described, the strut plate extends a considerable distance along the bottom of the sill and the

extensions on opposite sides of the body bolster and along the bottom of the body bolster on opposite sides of the sill, being rigidly secured to both the sill and body bolster.

5 In both modifications, the strut plate is so constructed that it does not interfere with the pivotal connection between the truck and body bolsters and so that the height of the draft gear and car floor is not increased.

10 It will be apparent that the present invention provides a very simple and economical construction at the joint between the center sill and body bolster which provides the necessary strength in the center sill to prevent distortion under buffing stresses without necessitating any departure from standard dimensions in the under frame members.

15 Furthermore, it is to be understood that the particular form of apparatus shown and described, and the particular procedure set forth, are presented for purposes of explanation and illustration and that various modifications of said apparatus and procedure can be made without departing from 20 my invention as defined in the appended claims.

What I claim is:

1. In a car underframe, a body bolster, a center sill having a recess on the under side 30 thereof of a width and depth to receive the body bolster, and a strut plate extending longitudinally of the sill beneath the recess, said plate being connected to the body bolster on opposite sides of the sill and having elongated channeled end portions having top 35 faces rigidly attached to the under side of the sill inwardly and outwardly of the recess.

2. In a car underframe, a body bolster, a center sill having a recess on the under side 40 thereof of a width and depth to receive the body bolster, and an elongated strut plate extending a substantial distance along the bottom of the sill inwardly and outwardly of the recess and rigidly attached to the bottom 45 of the sill on opposite sides of the recess, said strut plate having a widened center portion of greater width than the sill and attached to the body bolster, said strut plate having side portions converging from the center portion 50 toward the ends thereof and offset downwardly with respect to the portions of the plate attached to the sill.

3. In a car underframe, a body bolster, a center sill having a recess on the under side 55 thereof of a width and depth to receive the body bolster, and a strut plate having channeled end portions extending along the bottom of the sill inwardly and outwardly of the recess and rigidly attached to the sill, said strut plate having a widened central portion and reinforcing webs outwardly of the channeled portions which taper from the central portion toward the ends of the strut plate, whereby the strut plate forms a compression member across the bottom of said

recess which has sufficient strength to lower the neutral axis of the sill to approximately the line of action of the buffing stresses.

4. In a car underframe, a body bolster, a center sill having a body portion and an extension rigidly attached to the end of the body portion, said extension having a recess on the under side of a depth corresponding substantially to the height of the central portion of the body bolster and of a width to receive the body bolster, and an elongated strut plate having a wide central portion projecting to opposite sides of the sill, said strut plate having channeled portions extending substantially equal distances along the bottom of the sill inwardly and outwardly of the recess, the top faces of which are rigidly attached to the sill. 70 75 80

5. In a car underframe, a body bolster, a center sill having a body portion and extension members rigidly attached to the end of the body portion and having outer end portions spaced apart to provide draft arms, said extension members having webs and recesses on their under sides terminating short of the tops of the webs, said recesses being of a depth corresponding substantially to the height of the central portion of the body bolster and of a width to receive the body bolster, and an elongated strut plate, rigidly attached to the body portion of the sill and the extension members inwardly and outwardly of said recess, said strut plate being attached at its outer end to said draft arms and having a recess in its outer end to accommodate the draft yoke, the center portion of the plate engaging the body bolster on opposite sides of the sill. 85 90 95 100

6. In a car underframe, a body bolster, a center sill having a body portion and an extension rigidly attached to an end of the body portion, said extension having a recess on the under side of a depth corresponding substantially to the height of the central portion of the body bolster and of a width to receive the body bolster, and a strut plate having elongated channeled end portions rigidly attached to the bottom of the body portion and extension of the center sill and channeled side portions engaging the body bolster on opposite sides of the sill, said strut plate having webs at the sides thereof connecting said channeled portions. 105 110 115

7. In a car underframe, a body bolster, a center sill having a body portion and extension members having their inner ends rigidly secured to the opposite sides of the sill and the outer ends of said members being spaced apart to provide draft arms, said extension members having recesses on the under side thereof intermediate the ends thereof of a width and depth to receive the body bolster, and an elongated centrally widened strut plate extending across the recess and having elongated channeled portions rigidly secured 120 125 130

to the extension members and sill body outwardly and inwardly of the recess, said plate having laterally extending channeled portions secured to the body bolster on opposite sides of the sill and webs connecting the said channeled portions.

8. In a car underframe, a body bolster, a center sill having a body portion and extension members having their inner ends rigidly secured to the opposite sides of the sill, said members being spaced at their outer ends to provide draft arms, said extension members having recesses on the under sides thereof inwardly of the draft arms of a width and depth to receive the body bolster, and an elongated centrally widened strut plate extending across the recess and having elongated channeled portions the top faces of which are rigidly secured to the bottoms of

20 the extension members and sill body outwardly and inwardly of the recess, said plate having laterally extending channeled portions, the top faces of which are secured to the body bolster on opposite sides of the sill

25 and bracing webs on opposite sides thereof connecting the said channeled portions, said webs being below the level of said top faces.

9. In a car underframe, a body bolster, a center sill having an extension which is provided with a recess of a width and depth to receive the body bolster, a truck bolster having a central upwardly projecting boss and an annular rib concentric with the boss and forming therewith an annular bearing

35 groove, an elongated strut plate extending longitudinally of the sill across said recess and secured to the bottom of the sill and bottom of the body bolster, said sill, body bolster and boss having center pin apertures

40 and said strut plate having a center pin aperture substantially midway between its ends and registering with the boss, bolster and sill apertures, said plate having an annular bearing portion fitting in said annular

45 groove of the truck bolster.

In testimony whereof I affix my signature.
CLAUUS J. WERNER CLASEN.
